United States Patent Office.

H. H. MUNROE, OF LOUISVILLE, KENTUCKY.

Letters Patent No. 97,794, dated December 14, 1869.

IMPROVED COMPOUND FOR TREATING RHEUMATISM.

The Schedule referred to in these Letters Patent and making part of the same.

To all whom it may concern:

Be it known that I, H. H. MUNROE, of Louisville, in the county of Jefferson, and State of Kentucky, have invented a new and useful Improvement in Remedy for Rheumatism; and I do hereby declare that the following is a full, clear, and exact description thereof, which will enable others skilled in the art to make and use the same.

This invention relates to a new and useful improvement in remedy for curing rheumatism, and consists in the composition or compounds hereinafter named, which compounds are to be used simultaneously internally and externally.

The compound to be taken internally is marked A, and is composed of the following ingredients, combined in about the following proportions, viz:

Sirup of sarsaparilla, two ounces;

Sirup of white poppy, two ounces;

Iodine potash, six grains;

Gum-myrrh, three grains;

Tincture of aconite, twenty drops;

Pure whiskey, two ounces, and

One quart of pure soft water.

The compound to be applied externally, in connection with the above, is composed of the following ingredients, in about the proportions named, viz:

Cajeput oil, one ounce;
Oil of hemlock, one ounce;
Oil of sassafras, one and one-fourth ounce;
Oil of cedar, one ounce;
Oil of origanum, one ounce;
Tincture of aconite, four ounces;
Gum camphor, four ounces;
Pure new linseed-oil, one hundred ounces.

These compounds are to be used internally and externally, in connection with each other.

Of the internal compound, when combined with one quart of pure soft water, a wine-glass full is a dose.

The external compound (marked B) is applied to the affected part by rubbing with the hand, or otherwise.

Having thus described my invention,
I claim as new, and desire to secure by Letters Patent—

The above-described remedy for rheumatism, consisting of the compounds A and B, substantially as set forth.

H. H. MUNROE.
